Primary Examiner — David Muller(74) *Attorney, Agent, or Firm* — Scully Scott Murphy and Presser(57) **CLAIM**

The ornamental design for a component of injection device, as shown and described.

DESCRIPTION

FIG. 1 is a perspective view of a component of injection device, showing my new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken lines in the figures consisting of evenly sized dashes depict portions of the component of injection device that form no part of the claim.

1 Claim, 5 Drawing Sheets(56)
